WATER COOLED INK RESERVOIR FOR PRINTING PRESSES

Filed Sept. 25, 1926

- FIG. 2.-

INVENTOR:

John J. Halliwell
By
Edmond Congan Brown,
ATTY.

UNITED STATES PATENT OFFICE

JOHN J. HALLIWELL, OF TUCKAHOE, NEW YORK, ASSIGNOR TO R. HOE & CO., INC., OF NEW YORK, N. Y., A CORPORATION OF NEW YORK

WATER-COOLED INK RESERVOIR FOR PRINTING PRESSES

Application filed September 25, 1926. Serial No. 137,721.

My invention relates to printing presses of the intaglio type which are used in rotary photogravure printing, and particularly to the ink fountain of such presses and to means 5 for keeping the ink therein cool.

In rotary photogravure printing the ink used is preferably of a volatile nature, and if the temperature of the same is raised unduly, as is apt to be the case in hot weather, 10 or even in cool weather if the press becomes heated during a long continuous run, evaporation of the ink takes place, changing the character of the same and injuriously affecting the quality of the work.

One of the objects of my invention is to 15 prevent such change in the ink, by reducing evaporation of the same. This is effected by keeping the ink cool, in the manner herein-after described. Other objects of the invention will appear from the following description.

The invention consists in the novel construction, arrangement and combination of various devices, elements and parts, as set 20 forth in the claim hereof, one embodiment of the same being illustrated in the accompanying drawings and described in this specification.

In the said drawings,

Fig. 1 is an end view of one embodiment of 25 the invention, shown with one pair of printing cylinders, and

Fig. 2 is a side view of the same, the cylinders being omitted.

In carrying my invention into effect in the embodiment thereof which I have selected for illustration in the accompanying drawings and description in this specification, I provide a frame of suitable construction (not 30 shown in the drawings) in which is journaled the printing cylinder 11, which bears etched upon its surface in the usual manner the design to be printed. Below this cylinder is an ink reservoir 12, the bottom and walls 35 of which are of double construction, thus providing an intermediate space 13 for containing cool water or other fluid. In the preferred embodiment of the invention as shown in the drawings, I provide means for changing the 40 water in said intermediate space, so that the

same shall be always cool, such means comprising an inlet pipe 14 and outlet pipes 15.

The cylinder 11 rotates in the ink-fountain 12, and takes up ink upon its surface. A doctor-knife or scraper 16 is suitably mounted 55 and positioned so as to scrape against the surface of the cylinder 11 as it rotates, and remove the ink therefrom except where the etched-in lines retain the same. The web of paper to be printed (not shown in the drawings) passes over the roller 11 and between it and the impression cylinder 17 above it, and is printed as it passes through.

The operation of my invention has already 60 been sufficiently explained in the above description of its operation, and the advantages of the same also will be obvious from what has been above said.

Having thus described my invention, what 65 I claim as new and desire to secure by Letters Patent is as follows:

Cooling means for an ink reservoir of a printing press, comprising a jacket around said reservoir forming a space between said jacket and said reservoir adapted to contain 70 a cooling fluid, and means for supplying the fluid, comprising an inlet pipe for conveying said cooling fluid into said space and entering the bottom of said jacket at a point approximately midway between its two ends, 75 and an outlet pipe at each end of said jacket for conveying away the fluid in said space.

In witness whereof I have hereunto signed my name this 21st day of September, 1926.
